UNITED STATES PATENT OFFICE.

JULIUS KAHN, OF YOUNGSTOWN, OHIO.

REINFORCED-CONCRETE BUILDING CONSTRUCTION.

1,285,211.

Specification of Letters Patent. Patented Nov. 19, 1918.

Application filed November 4, 1916. Serial No. 129,417.

To all whom it may concern:

Be it known that I, JULIUS KAHN, a citizen of the United States, and residing at Youngstown, in the county of Mahoning 5 and State of Ohio, have invented a new and Improved Reinforced-Concrete Building Construction, of which the following is a specification.

The present invention relates to a reinforced concrete floor supported on columns; its object is to produce a construction wherein the bars or rods are more economically arranged in the slabs and wherein the stresses are more evenly distributed from 10 the slabs into the tops of the columns than heretofore. The nature of the invention will be pointed out later, but to facilitate the understanding thereof three features of decided importance may be noted at the outset: (1) The stresses are transmitted from the slabs into a column head of a horizontal cross-section considerably greater than the cross-section of the column proper by a main reinforcement consisting of bars which 15 lie substantially parallel to and are spaced from each other in the head, said bars passing entirely across the latter from side to side and extending therefrom into the slabs on diverging lines; (2) the angular distribution and the length of the bars is made to correspond to the stresses which are to be carried to the heads; (3) an auxiliary reinforcement consisting of two intersecting sets of bars arranged parallel to the center lines 20 of the columns and properly spaced from each other throughout a zone of considerable width is employed.

In the drawings, which show a preferred embodiment of the invention, Figure 1 is a plan view of one floor panel with enough of the surrounding panels to illustrate the general arrangement of the reinforcement. Fig. 2 is a section on the line 2-2 of Fig. 1. Fig. 3 is an enlarged section corresponding 25 to the right hand portion of Fig. 2.

The reinforced concrete columns 1 of suitable construction are located at the corners of a floor panel 2 (preferably square or rectangular) and are provided with flaring 30 heads 3 that may be shaped, if desired, to form dropped panels 4. Passing across the upper portions of column heads (which may be regarded as extending to the upper surface of the floor) on lines parallel to the 35 center lines joining adjacent columns are two sets of cantaliver or top bars, each set

lying in a single horizontal plane and having its members spaced apart from one another. The reinforcement, in crossing the column heads, therefore occupies very little depth 60 and may be most advantageously placed with reference to the transmission of stress. It will be observed that each set of bars includes the relatively short bars 5 and the relatively long bars 6 and 8, and that the end portions of these bars diverge from one another substantially from the periphery of the head of the corresponding column, the angles which the end portions make with the adjacent edges of the head being substantially 65 equal. The bars 6, after passing over the column head, dip downwardly into the lower portion of the slab and preferably extend a short distance into the head of the adjacent column; the bars 8 of similar contour, but preferably of less length, terminate in the slab on either side of the center lines of columns; while the ends of the short bars 5 preferably lie wholly in the upper portion of the slab and extend outwardly beyond the inflection points. Thus 70 the bars 6 resist negative bending moments over the column heads as well as positive moments midway between the columns and substantially on the lines of the column centers at the sides of the rectangular panels, and the bars 8 have a like function with respect to the positive stresses in the panels at points somewhat farther removed from the corresponding center line of columns. 75 The bars 5 take negative bending moments in the slabs in the vicinity of the inflection points and also resist the negative moments over the column heads. It will be noticed that the bars 6 and 8 for a given column cross the corresponding bars for the adjacent columns at substantially the mid-point of the span. The bars 5, 6 and 8 constitute 80 what may be termed the main reinforcement. 85

Besides the main reinforcement there is used an auxiliary reinforcement consisting of two sets of spaced beam or bottom bars 9, the bars of each set for a given panel being parallel and crossing those of the other set 105 in the central portion of the panel, it being understood that, in this vicinity, they lie near the lower face of the slab to take positive bending moments. As the auxiliary bars approach the lines joining the edges of the 110 column heads, they rise up into the upper face of the slab, and preferably pass en-

5 entirely across the space defined by the side lines of the column heads, as indicated at the right hand side of Fig. 2. Thus the major part of the loads at the central portions of the panels are transmitted into the upper portions of the slab sections defined by the side lines referred to above, and are then carried at substantially right angles by the bars 6 to the heads of the columns; 10 in this connection it will be noted that some of the central loads are carried directly to the columns by those bars 8 which extend at the greatest angle to the center lines of adjacent columns. The bars 9 in passing 15 through the upper portion of the slab above the bars 6 take the negative transverse bending moments, as will be readily understood.

20 In this construction, the use of a ring or the like (in which the actual stresses in the bars are necessarily greatly multiplied) above the column heads is avoided, as is the objectionable distribution of the steel of those systems in which the bars pass entirely across the column heads in bundles; 25 the use of unnecessary reinforcement is also avoided, and the computation of stresses is facilitated. The spacing of the bars in the heads is readily secured by the use of proper spacing bars, as will be readily understood.

30 I claim:

1. In a building comprising capped columns arranged in rows at an angle to each other and a flat slab panel resting thereon, a system of flat slab reinforcement consisting of a group of cantaliver or top bars, the cantaliver group consisting of two sets of bars arranged at right angles to each other over the columns, the bars of each set being parallel to each other substantially throughout the column caps and radiating from the edge of said caps into the panel and being of various lengths, the bottom bar group consisting of two sets of bars arranged in the form of a cross in the center of the panel, the bars of each set being parallel with each other and extending from the center of the panel to a place midway between the columns of the corresponding row.

2. In a building comprising capped, reinforced concrete columns arranged in rows at an angle to each other and a flat slab panel resting thereon, a system of flat slab reinforcement consisting of a group of cantaliver or top bars, and a group of beam or bottom bars, the cantaliver bars being

parallel with each other substantially throughout the column caps, and radiating into the panel from the edges of the column caps and being of various lengths, some, at least, extending across the supported panel.

3. In a building comprising capped, reinforced concrete columns arranged in rows at an angle to each other and a flat slab panel resting thereon, a system of flat slab reinforcement consisting of a group of cantaliver or top bars, and a group of beam or bottom bars, the cantaliver bars being parallel with each other substantially throughout the column caps and radiating into the panel from the edges of said caps and being of various lengths, some, at least, extending across the supported panel, the bottom bars being arranged in two bands which cross each other substantially in the center of the panel and extend along the bottom of the panel to points near the rows of columns and then up and through the top of the panel substantially midway between the columns of the corresponding row.

4. In a reinforced concrete building comprising columns having relatively large caps and a slab panel supported thereby, reinforcing comprising a group of cantaliver or top bars, and a group of beam or bottom bars, the cantaliver bars passing in parallel sets substantially entirely across the tops of the column caps and radiating from the edges of said caps to reinforce substantially all points in the panel and being varied in length to suit the stresses existing at various points in the panel.

5. In a building comprising capped, reinforced concrete columns arranged in rows at an angle to each other and a flat slab panel resting thereon, a system of flat slab reinforcement comprising a group of cantaliver bars arranged in two sets which cross each other over the columns in lines parallel to the rows of columns, the bars of each set being parallel to each other substantially throughout the column caps and lying in a single horizontal plane, the ends of the bars of each set diverging from one another into the panel from the edges of the column caps and being of various lengths, some at least, extending across the supporting panel.

In testimony whereof I sign this specification.

JULIUS KAHN
